1 Claim

ABSTRACT OF THE DISCLOSURE

Combustion apparatus for a gas turbine engine comprising an annular air jacket casing, an inlet and an outlet at opposite ends thereof respectively, an annular flame tube having inner and outer walls within the air jacket and defining an inlet and outlet, a wall separating the flame tube into two zones with which the inlet and outlet communicate respectively, the inlet of the flame tube being divided into portions communicating with the zones respectively, and openings in the wall providing communication between the two zones at positions longitudinally aligned with inlet portions to the second zone.

This invention has for its object to provide combustion apparatus, for gas turbine engines, in a convenient form.

The present invention resided in combustion apparatus for a gas turbine engine comprising an annular air jacket having inner and outer walls defining an inlet and an outlet at the upstream and downstream ends respectively, an annular flame tube having inner and outer walls spaced from those of the air jacket the flame tube walls also defining an inlet and an outlet at the upstream and downstream ends respectively, a wall separating the flame tube into two zones in one of which combustion is intended to take place, and with the second of which the flame tube outlet communicates, the flame tube inlet being divided into two sets of alternating openings affording communication with the two zones respectively, and further openings near the upstream end of the flame tube and affording communication between the two zones for the escape of the products of combustion from the combustion zone to the second zone, the further openings being longitudinally aligned with the inlet openings into said second zone, there being means for introducing fuel to be burnt into the combustion zone.

An example of the invention is illustrated in the accompanying drawings in which FIGURE 1 is a longitudinal cross-sectional view of combination apparatus constructed in accordance with the invention, and FIGURE 2 is a transverse cross-sectional view on the line II—II in FIGURE 1.

In the example shown there is provided combustion apparatus for a gas turbine engine comprising an annular air jacket having inner and outer walls 10, 11 within which is disposed in spaced relation to the air jacket walls an annular flame tube also having inner and outer walls 12, 13. At one end, referred to as the upstream end, the inner and outer air jacket walls converge to form an inlet 14 from a compressor (not shown) and at the downstream end is defined an outlet. The flame tube downstream end has an outlet 15 within the air jacket outlet, to a turbine (not shown).

The flame tube is divided into inner and outer zones in-

2

dicated by numerals 16 and 17 respectively, and the upstream end of the flame tube has alternating openings 18, 19 (see FIGURE 2) for entry of air from the inlet 14 of the air jacket to the two zones 16 and 17 respectively, there being outwardly extending deflector plates 20 in the openings 19 leading to the outer zone 17. Disposed in the openings 18 leading to the inner zone 16 are respective fuel burner nozzles 21 and each of the openings 18 has side panels 22 to tend to separate the stream of air entering the zone 16 and those leaving this zone through further radially outwardly presented openings 23 in the wall 24 separating the two flame tube zones 16, 17, the openings 23 being respectively aligned lengthwise of the flame tube with the openings 19.

In use, primary air and liquid fuel enter the zone 16, in which combustion takes place, through the openings 18 and between the panels 22. Within the zone 16, the mixture tends to follow a generally toroidal path as combustion takes place. The products of combustion leave the zone 16 through the openings 23 and in doing so they are mixed with dilution air entering through the openings 19 and finally the mixture of the products of combustion and dilution air leave the flame tube through the outlet 15. As illustrated there is, extending into the zone 16, and secured to the inner flame tube wall 12, a deflector plate 25 which is positioned to modify the flow of gasses through the zone 16 to tend to form two toroidal flow patterns within the zone.

Having thus described my invention what I claim as new and desire to secure my Letters Patent is:

1. Combustion apparatus for a gas turbine engine comprising an annular air jacket having inner and outer walls defining an inlet and an outlet at the upstream and downstream ends respectively, an annular flame tube having inner and outer walls spaced from those of the air jacket, the flame tube wall also defining an inlet and an outlet at the upstream and downstream ends respectively, a wall separating the flame tube into two zones, in one of which combustion is intended to take place, and with the second of which the flame tube outlet communicates, the flame tube inlet being divided into two sets of alternating openings affording communication with the two zones respectively, and further openings near the upstream end of the flame tube and affording communication between the two zones for the escape of the products of combustion from the combustion zone to the second zone, the further openings being longitudinally aligned with the inlet openings into said second zone, means for introducing fuel to be burnt into the combustion zone, and a deflector in the combustion zone so positioned as to produce two toroidal flows of gases within said zone.
